(57) CLAIM

The ornamental design for a decorative wall panel, as shown and described.

DESCRIPTION

FIG. 1 is a perspective view of a decorative wall panel of the first embodiment, the decorative wall panel having quarter-round voids at the two front corners of the decorative wall panel;

FIG. 2 is a rear view of the decorative wall panel of the first embodiment;

FIG. 3 is a top view of the decorative wall panel of the first embodiment;

FIG. 4 is a front view of the decorative wall panel of the first embodiment;

FIG. 5 is a bottom view of the decorative wall panel of the first embodiment;

FIG. 6 is a left side elevational view of the decorative wall panel of the first embodiment, the side view enlarged to show one of the quarter-round voids having scrape marks therein;

FIG. 7 is a right side elevational view of the decorative wall panel of the first embodiment, the side view enlarged to show one of the quarter-round voids having scrape marks therein;

FIG. 8 is an enlarged fragmentary perspective view of the right hand portion of the decorative wall panel of FIG. 1, the quarter-round void having scrape marks therein, it being understood that the left hand portion includes a similar quarter-round void with scrape marks;

FIG. 9 is an enlarged fragmentary perspective view of the front right hand portion of a decorative wall panel showing a second embodiment, the sole difference being that the quarter-round void is smooth, it being understood that the left hand portion includes a similar quarter-round void and that all other surfaces are the same as the first embodiment as shown in FIGS. 2-7;

FIG. 10 is an enlarged fragmentary perspective view of the right hand portion of a decorative wall panel showing a third embodiment, the sole difference being that the right and left front corners include a quarter-square void, it being understood that all other surfaces are the same as the first embodiment as shown in FIGS. 2-7; and,

FIG. 11 is a front perspective view of a decorative wall panel showing a fourth embodiment, the sole difference being that the decorative wall panel is of intermediate length, it being understood that all other surfaces are the same as the first three embodiments as shown in FIGS. 1-10.
